UNITED STATES PATENT OFFICE.

WILLIAM H. AVERILL, OF BOSTON, MASSACHUSETTS.

LOOSE-LEAF BINDER.

1,208,724.

Specification of Letters Patent. Patented Dec. 19, 1916.

Application filed December 15, 1915. Serial No. 66,920.

To all whom it may concern:

Be it known that I, WILLIAM H. AVERILL, a citizen of the United States, residing at Boston, in the county of Suffolk and State 5 of Massachusetts, have invented new and useful Improvements in Loose-Leaf Binders, of which the following is a specification.

This invention has for its object to provide a loose leaf binder, the jaws or leaf-confining members of which are adapted to be securely confined at various distances apart, to confine a pile of leaves of any desired thickness, and to be quickly and conveniently separated and confined.

15 The invention is embodied in the improvements which I will now proceed to describe and claim.

Of the accompanying drawings forming a part of this specification: Figure 1 represents a perspective view of a loose leaf binder embodying my invention; Fig. 2 represents a section on line 2—2 of Fig. 1; Fig. 3 represents a view similar to Fig. 2, showing the latch separated from the toothed bar; Fig. 4 represents a section on line 4—4 of Fig. 2; Figs. 5 and 6 represent fragmentary sectional views showing the inner and outer tubular post; Fig. 7 represents a side view and Fig. 8 a perspective view of the plunger; Fig. 9 represents a perspective view of the latch; Fig. 10 represents a side view of the inner tubular post and the latch engaged therewith.

The same reference characters indicate the 35 same or similar parts in all the views.

In the drawings: 12 and 13 represent opposed jaws, which preferably have flanges 12^a and 13^a in sliding contact with each other and forming the back portion of an adjustable cover, the side portions of which are formed in part by the jaws and in part by cover sections 14 flexibly connected with the jaws at 15. The lower jaw 13 is provided with a tubular outer post member 16, and the upper jaw 12 is provided with a smaller tubular inner post member 17 entering and movable in the member 16, the two members constituting a telescopic hollow post. In practice, two of said posts are provided, but 45 as said posts and the hereinafter described devices coöperating therewith are alike in construction a description of one will suffice. Each jaw and its post member are rigidly connected and may be made of sheet or thin 55 plate metal. The exposed surfaces of the jaws may be covered with a veneering of

leather or other suitable finishing material, not shown.

To the jaw 13 is rigidly attached a bar 19, one edge of which is toothed, as shown by 60 Figs. 2 and 3, said bar being contained in the outer post member 16, and arranged to enter the inner post member 17.

20 represents a latch which is oscillatively connected with the upper jaw 12, and is 65 adapted to engage either of the teeth of the bar 19, as indicated by Fig. 2, and to be separated from said bar, as indicated by Fig. 3. The latch is preferably connected with the outer jaw by means of a hook 20^a on one 70 end of the latch, and a slot 21 in the inner post member 17, the hook loosely entering the slot so that a swinging movement of the latch is permitted.

I have provided latch-controlling means 75 normally holding the latch in engagement with the bar and manually operable to separate the latch from the bar, said means being preferably organized as follows: 22 represents a plunger adapted to move in the 80 inner post member 17, and provided at its outer end with a head or push button 23. The plunger is also provided with an outer cross-bar 24 and an inner cross-bar 25. A spring 26 located in an enlargement or 85 spring chamber 27 at the outer end of the post member 17 normally holds the plunger in the raised position shown by Fig. 2. The latch is provided with an outer inclined face 28 and with an inner inclined face 29. The 90 relative arrangement of the said cross-bar and faces is such that when the plunger is raised by the spring the cross-bar 25 coöperates with the face 29 in holding the latch in engagement with the bar 19, as shown by 95 Fig. 2. When the plunger is depressed the cross-bar 24 coöperates with the face 28 in holding the latch separated from the bar, as shown by Fig. 3.

A plurality of loose leaves 31 perforated 100 to receive the outer post members 16 may be assembled on the lower jaw 13 and then confined by inserting the inner post members 17 in the outer post members and moving the upper jaw downwardly the required 105 distance, the operator holding the plungers depressed by pressure of his thumbs thereon. When the outer jaw is located the release of the plungers causes the engagement of the latches with the toothed bars, so that the 110 jaws are locked together. The upper jaw may be released by the depression of the

plungers, and raised from the lower jaws while the plungers are held depressed.

The hook 20^a is preferably slotted to form prongs 20^b originally arranged as shown by Fig. 9. After the hook is inserted in the slot 21, the prongs 20^b may be bent laterally, as shown by Figs. 4 and 10, to prevent the withdrawal of the hook from said slot.

Having described my invention, I claim:

10. 1. A loose leaf binder comprising opposed jaws, each having a tubular post member, the two members constituting a telescopic hollow post, a toothed bar and a bar-engaging latch within said post, the bar being rigidly connected with one jaw, and the latch pivotally connected with the post member of the other jaw, a manually movable plunger in the post, and a spring normally holding the plunger in a raised position, the said latch and plunger being provided with complementary latch-shifting means coöperating with said spring to normally hold the latch in engagement with the bar, and acting to separate the latch from the bar when the plunger is manually depressed.

2. A loose leaf binder comprising opposed jaws, each having a tubular post member, the two members constituting a telescopic hollow post, a toothed bar and a bar-engaging latch within said post, the bar being connected with one jaw, and the latch with the other jaw, and a manually movable spring-raised plunger in the post, the latch being provided with outer and inner inclined faces, and the plunger with outer and inner cross-bars coöperating in normally holding the latch in engagement with the bar, and in separating the latch from the bar when the plunger is manually depressed.

3. A loose leaf binder comprising a jaw having an outer tubular post member and a toothed bar within the same, another jaw having an inner tubular post member movable in said outer member, a latch oscillatively engaged with the inner post member and adapted to engage the said bar, said latch being provided with outer and inner

inclined faces, a plunger movable in the inner post member and provided with outer and inner cross-bars coöperating with said inclined faces, and a spring normally raising said plunger and holding the latch in engagement with the bar.

4. A loose leaf binder comprising a jaw having an outer tubular post member and a toothed bar within the same, another jaw having an inner tubular post member movable in said outer member, a latch oscillatively engaged with the inner post member and adapted to engage the said bar, said latch being provided with outer and inner inclined faces, a plunger movable in the inner post member and provided with outer and inner cross-bars coöperating with said inclined faces, and a spring normally raising said plunger and holding the latch in engagement with the bar, the inner post member being provided with an enlargement forming a spring-receiving recess.

5. A loose leaf binder comprising a jaw having an outer tubular post member and a toothed bar within the same, another jaw having an inner tubular post member movable in said outer member and provided with a slot, a bar-engaging latch having a hook movable loosely in said slot, and a manually movable spring-pressed plunger in the post, said latch and plunger being provided with complementary latch-shifting means.

6. A loose leaf binder comprising a jaw having an outer tubular post member and a toothed bar within the same, another jaw having an inner tubular post member movable in said outer member and provided with a slot, a bar-engaging latch having a hook movable loosely in said slot, said hook being provided with means for preventing its withdrawal from the slot, and a manually movable spring-pressed plunger in the post, said latch and plunger being provided with complementary latch-shifting means.

In testimony whereof I have affixed my signature.

WILLIAM H. AVERILL.
